SHEET SEPARATING DEVICE

Louis Trompier, Villeurbanne, France

Application March 8, 1934, Serial No. 714,587
In Germany March 9, 1933

3 Claims. (Cl. 271—36)

The present invention concerns an automatic feed for sheets of paper, cards, envelopes or any other thin and flexible material occurring in sheets, the principal characteristic consisting of a large output and extremely simple and certain functioning.

This system of automatic feed is essentially characterized in that the sheets, cards, envelopes etc., are arranged in a pile in front of a rotary feed system which draws off, in the direction of its movement, the first sheet of this pile.

Under the action of the driving force to which it is subjected, the first sheet slides over the following one and is introduced into a curved channel for transmission to the delivery end without the following sheet or sheets being simultaneously carried along owing to their disposition relative to the direction of the curved delivery channel and the section of its opening, which are adjusted so as to permit only one sheet to pass at a time.

This system of automatic feed is based on drawing off at considerable speed a sheet of paper carried into a curved passage of adjustable cross section at the end of which is placed a pressure spring which relieves the exit by assisting the fall of the preceding sheet, card, envelope etc.

The curved shape of this channel necessitates a system of feeding and delivering having an adhesion sufficient to permit the sheet to be carried into this channel in spite of the resistance opposed to its forward movement by this curvature. In this manner it is ensured that several sheets will not pass simultaneously, the adhesion being insufficient to carry along the following sheet.

In order to prevent the succeeding sheet from being started inopportune by the smooth part of the driving system, and to annul the effect of this, a light spring, which holds it, is arranged at a very short distance (a few millimetres) below the entrance to the curved channel.

This automatic feed may or may not be completed by any appropriate device which enables the feed of the sheet or envelope to be regulated, in order that it shall be delivered in the intervals or according to the rhythm of the machine or of the member which receives them; printing machines, counting, gumming, duplicating machines or the like.

The feeding action may also be increased by arranging, in the adhering material, or by replacing it with, suction orifices, the action of

which only occurs at the appropriate instant, in a manner already known.

This regulating device may consist of a known system, either of a set of rocking fingers or cams which are applied at intervals to push against the pile of sheets which is to be fed, or in the case of a rotary feeding system, of one or several smooth parts, which thus have no driving action, separating those of adhesive material.

As a consequence, the invention has in view, and this by way of new industrial products, automatic feeds comprising the whole or partial application of similar devices.

It can be quite easily understood with the aid of the following supplementary description and of the diagrammatic drawing attached, which description and drawing are, of course, given purely by way of indication.

Figures 1 and 2 show the apparatus in side elevation at the instant when one sheet is being fed and the preceding one is falling.

Figure 3 is a plan view.

According to the invention the apparatus in its essential elements consists of an inclined plane or fixed supporting table 1 on which is arranged the pile 2 of paper, sheets, envelopes or the like, which are to be taken one at a time, in such a manner that they descend by gravity.

If necessary, their descent can be assisted by a known system, for example by means of a pressure plate 3 shown dotted in the drawing, or by some member having a spring or other device pressing against the upper part of the pile. This pile is arrested at its base by a feed system consisting, in the case shown in the drawing, of a roller 4 whose periphery has a smooth part 5 and another 6 of rubber, gelatine or other material causing adhesion, against which it bears. It also bears with its upper part against a support 7 which is movable in one or other of the directions of the arrow 17, in such a way as to adjust perfectly the orientation of the sheet 11 relative to the opening of the channel.

The foot of the sheets or envelopes of the pile 2 rests on a movable support 9 having cheeks 45 which, by means of the screw and knurled head 10, can be moved towards or away from the roller 4, in such a way as to reduce or increase the space left free between the periphery of this and the said movable support 9 in order to form 50 the curved feed passage 12.

When rotating in the direction of the arrow 8, the wheel 4 feeds by adherence the first sheet or envelope 11 of the pile 2 into the said curved passage. Thus drawn off, it slides against the 55

succeeding sheet or envelope and is delivered by the passage 12 towards the machine where it is to be used.

In order to ensure perfect separation between the sheets the small spring 16 attached to the strut 14 closes the curved channel a few millimetres below its entrance. By thus preventing a sheet from starting inopportune, it is ensured that the feed will only take place when the adherence is sufficient to overcome the resistance due to the passage in the curved channel 12 and that due to the small spring 16.

With the object of ensuring a perfect separation of the sheets, and a better fall of that discharged, there is also arranged at the exit from the passage 12 a spring 13 having a suitable play, fixed to a strut 14 above the roller 4. An orifice 15 provided in its median part enables it to bend without colliding with anything.

When the sheet or envelope 11 reaches the end of the passage 12 it slides underneath the spring 13 which is raised and which presses on it. When this sheet has completely left the passage 12, the pressure of the spring 13 causes it to fall as shown in Figure 1.

In order to facilitate the discharge, a cylinder 22 of a material causing adherence can be arranged at the end of the passage 12 and is driven by friction from the wheel 4, as the said cylinder and wheel are always wider than the sheet to be driven.

For manipulating certain qualities of paper it is possible that the driving effort produced by the material causing adhesion may be insufficient. In this case it may be increased by using, in combination with the above system, vacuum suction such as is commonly employed in printing machines.

In the case of the apparatus shown in the drawing, along one or more of the surfaces of the adherent part of the wheel 4 several orifices are provided, of suitable shape (18) with channels 19 opening into a central channel 20 which is itself in communication, through a tube 21, with an air pump or some other apparatus for reducing the pressure, not shown in the drawing. By means of a rotating valve of some known system, the suction is produced from the instant the paper

is seized until the instant it falls. These orifices 18 are closed by some system in accordance with the width of the sheet being fed.

What I claim and desire to secure by Letters Patent of United States is:—

1. In a sheet separating and feeding device having a feeding and discharging roller adapted to engage against a pile of sheets standing edge-wise in an inclined position, a fixed supporting table disposed adjacent to said roller, and an adjustable guide block upon said table supporting said pile of sheets, having one end thereof concave in substantially concentric conformity with the arcuate surface of said roller and spaced an alterable distance therefrom so that a uniform curved delivery channel results between said block and roller, which is adjustable by adjustment of said block upon said table to the thickness of a single sheet intended to pass through said channel.

2. In a sheet separating and feeding device according to claim 1, a doubled and bent guide member disposed in front of the pile of sheets upon the guide block, having one end serving as a resilient arm or spring penetrating into the curved delivery channel in order to prevent a second sheet from accidentally sliding into the channel and accompanying a sheet being delivered through said channel and the second end extending downward past the circumference outline of the roller so as to effect final separation and delivery of the single sheet from said channel in a predetermined direction.

3. In a sheet separating and feeding device according to claim 1, the combination of the guide member located in front of the pile of sheets upon the guide block having the lower end thereof penetrating into the curved delivery channel in order to serve as a spring preventing a second sheet from accidentally sliding into the channel and accompanying a single sheet being delivered through said channel, and a second guide member also disposed in front of said pile having the lower end extending downward past the circumference outline of the roller and effecting final separation and delivery of the single sheet from said channel in a predetermined direction.

LOUIS TROMPIER.
